UNITED STATES PATENT OFFICE.

CYRUS E. MEAD, OF DAYTON, OHIO, ASSIGNOR TO THE MEAD ENGINE COMPANY, OF DAYTON, OHIO, A CORPORATION OF OHIO.

VALVE-ACTUATING DEVICE FOR EXPLOSIVE-ENGINES.

1,111,665.

Specification of Letters Patent. Patented Sept. 22, 1914.

Application filed January 22, 1912. Serial No. 673,805.

To all whom it may concern:

Be it known that I, CYRUS E. MEAD, a citizen of the United States, residing at Dayton, in the county of Montgomery and State of Ohio, have invented certain new and useful Improvements in Valve-Actuating Devices for Explosive-Engines, of which the following is a specification, reference being had therein to the accompanying drawing.

This invention relates to valve-actuating devices for explosive engines and more particularly to a device for actuating a rotary valve in an engine comprising a plurality of units.

The objects of the invention are, first, to provide a valve-actuating device which will permit of the valve being formed in a plurality of relatively short sections, there- 20 by reducing the torsional strain on the valve and further materially facilitating the manufacture of the same; second, to so construct the device that the sections of the valve may be simultaneously adjusted; and 25 third, to mount the actuating device so as to reduce the strain or thrust on the valves to a minimum and to permit the free expansion and contraction of the valves.

In the accompanying drawings, Figure 1 30 is a side elevation of an engine embodying my invention; Fig. 2 is an elevation of the valve-actuating device; Fig. 3 is a section taken centrally through the device and the adjacent portions of the valve chambers; 35 and Figs. 4 and 5 are sections taken centrally of slightly modified forms of the actuating device.

In these drawings I have illustrated the invention as applied to a four cylinder gas 40 engine having its cylinder cast in units, each unit comprising two cylinders. These units are indicated at 1 and 2, respectively and are spaced apart, as is customary. Mounted in both units so as to control the intake and 45 exhaust to and from all the cylinders of the engine is a rotary valve 3. A valve of the length required for a four cylinder engine is difficult to manufacture and when rotation is imparted thereto at one end thereof 50 it is subjected to severe torsional strain. To overcome both the difficulties in manufacture and the torsional strain on the valve I mount the actuating device between the two units of the engine and form the valve in two separate parts, one of which is 55 mounted in each of the units and which are so connected with the actuating device as to be rotated in unison thereby. By mounting the actuating device at the middle of the valve it will be obvious that the torsional strain to which the valve is subjected is very greatly reduced and it is equally obvious that as a manufacturing proposition it is much easier to work two short valves to true cylindrical shape than it is 60 a single valve equal to the length of the two short valves. In carrying out the invention I prefer to mount the actuating device independently of the valves and to connect the same to the valves in such a manner that the latter will be free to expand and contract and will not be subjected to any thrust or strain. In the present construction I have accomplished this by mounting on one of the units a hollow stud 70 4 having a longitudinal opening in alignment with the valve chambers of both units. This stud may be secured to the engine in any suitable manner. As here shown it is secured thereto by means of screws 5 extending through apertured lugs 6. The outer portion of the stud 4 is provided with a cylindrical bearing surface upon which is mounted the actuating member which, in the present construction, comprises a 80 sprocket wheel 7 and, as here shown, anti-friction rollers 8 are interposed between the sprocket wheel and the bearing surface of the stud. A collar 9 is rigidly secured to the outer end of the stud to hold the actuating member and the friction rollers against movement longitudinally of the hub. This connection is here shown as formed by providing the collar with an inwardly extending screw-threaded boss 10 85 adapted to be screwed into the screw-threaded outer portion of the stud. The two valve members 3 are provided on their adjacent ends with inwardly extending stems 11 non-circular in cross section and these two parts 90 of the valve are connected one to the other by means of a sleeve 12 fitting loosely within the hollow stud 4 and having its longitudinal opening of a shape corresponding substantially to the cross sectional shape of 100 the non-circular stems 11. The stems of the valve parts are adapted to extend into the opposite ends of the sleeve and the fit be-

tween the stems and the sleeve is such as to prevent any rotary movement of the stems relatively to the sleeve but at the same time to permit of the longitudinal movement of the stems relatively to the sleeve and thus permit of the expansion and contraction of the valve. The sleeve which serves to connect the valves one to the other also serves to connect the same with the actuating member and to this end has rigidly secured thereto four radial arms 13 constituting a spider and having their outer portions bent inwardly and connected with the sprocket wheel. The connection between the spider and the actuating member is preferably an adjustable one and to this end the connection is formed by means of screws 14 extending through slots 15 in the sprocket wheel and screwed into apertures in the outer ends of the arms 13 of the spider.

It is also desirable that means should be provided whereby the valves will be caused to occupy a fixed relation to the driving member or gear when these two parts are operatively connected one with the other, thus enabling the valve to be timed and then removed and re-inserted without affecting its timing. This may be very readily accomplished by providing the sleeve 12 with an irregular opening and shaping the stem of the valve section to correspond with this opening as, for example, by providing the opening with three angular corners and one round corner and rounding one corner of the stem in the same manner. With this construction after the sleeve has once been adjusted with reference to the driving member to time the valve, the valve may be removed and re-inserted without interfering with its adjustment and without interfering in any way with the timing of the valve. The removal of a section of the valve is accomplished by detaching the removable cap 16 at that end of the valve opposite the driving gear and simply withdrawing the valve section.

It will be obvious that the driving member may be supported and connected with the valve sections in different ways and, in Figs. 4 and 5, I have, by way of illustrating the changes which are possible, shown two modified forms of the device. In Fig. 4 the supporting device, which is indicated at 17, is in the form of a housing and has mounted therein two ball races 18. The driving member, which is shown in the form of a worm wheel 19 has a hub 20 to which is secured, on opposite sides of the worm wheel, ball races 21. Balls 22 are mounted in race ways 18 and 21 and the driving member is thus supported by roller bearings upon the housing. Instead of utilizing the hollow sleeve connection shown in Figs. 1 to 3 I have, in this instance, mounted within the hub a shaft 23 connected at its opposite ends with the valve

members and adjustably connected with the hub 20. This connection, in the present instance, is formed by providing the shaft 23 with screw threads 24 near each end thereof, which threads engage corresponding threads 70 in the adjacent end portions of the hub. The hub and shaft are locked in fixed relation by means of nuts 25 mounted on those portions of the shaft extending beyond the hub. The connection between the ends of the shaft and 75 the respective valve members may be accomplished in any suitable manner. In the present instance the ends of the shaft are slotted, as indicated at 26, and the adjacent ends of the valve sections are also slotted, 80 as indicated at 27, the respective slots extending, when in their normal positions, at right angles one to the other. A connecting member 28 is interposed between the end of the shaft and the end of the respective valve 85 section and has keys or projections 29 and 30 arranged to engage the slots in the valve section and shaft respectively, thus connecting the parts one to the other and retaining them in their fixed relation but at the same 90 time permitting the valve section to have a limited longitudinal and radial movement relatively to the driving member and eliminating all strain or thrust upon the valve.

In Fig. 5 a similar construction is followed save that the shaft is connected with the hub and the valve sections in a different manner. In this instance the hub 20 of the driving member is provided with a longitudinal tapered opening and the shaft 31 is 100 tapered to fit within the tapered opening of the hub. Those portions of the shaft which extend beyond the ends of the hub are screw-threaded and nuts 32 mounted on these screw-threaded portions serve to retain the hub and the shaft in adjusted and operative relations. The connection between the valve sections and the shaft is similar to that first described. The tapered shaft 31 is provided with a longitudinal opening angular in cross 105 section, into which extend the angular stems 33 of the valve sections.

Another feature of importance which will be noted in the several constructions herein illustrated is the relation of the ends of the 115 valve members to their respective valve chambers. In each instance the end of the valve member is flush with or extends slightly beyond the corresponding end of the valve chamber. If the valve member terminates short of the end of its chamber there is a tendency for the oil or other lubricating agent employed to lubricate the valve to work its way beyond the end of the valve and there to bake or become hardened and form 120 a very hard shoulder which interferes with the longitudinal movement or removal of the valve member. Also, if the valve terminates short of the end of its chamber the wear tends eventually to form a shoulder in the 130

chamber. By causing the valve sections, at both ends, to extend to, or slightly beyond the corresponding ends of the valve chambers both of these undesirable results are 5 avoided and there is no accumulation of carbon or hardened oil in the ends of the valve chambers and there is no shoulder worn within the valve chambers. Consequently, the valve has free and unobstructed longitudinal movement to permit either of the 10 expansion and contraction or play of the valve or to permit of its removal.

It will be apparent that the actuating device for the valve is supported independently of the valve and that the latter is thus entirely relieved of the strain and thrust due to the operation of the actuating device and also that the valve is free to expand and contract inasmuch as it has longitudinal movement relatively to the actuating device. Moreover, it will be apparent that the connection between the valve sections and the actuating device is such as to permit the two parts of the valve to be 20 simultaneously and easily adjusted and to retain these two parts of the valve in their proper relative positions; and further, that the connection is such as to permit the valve to be readily withdrawn and replaced and 25 to permit this to be accomplished without interfering with the adjustment, or timing, of the valve. It will also be apparent that the arrangement of the valve actuating device between the two units of the engine 30 enables the valve to be made in two or more relatively short sections which not only facilitates the manufacture of the valve but very materially reduces the torsional strain thereon.

While I have shown and described one embodiment of the invention with several modifications thereof it will be understood that these are chosen for the purpose of illustration only and that the invention may 45 be embodied in many forms. In the present construction the engine as a whole is built in two units but the invention is capable of embodiment in engines otherwise constructed, it being only necessary that the 50 valve chamber for the rotary valve should be divided into two parts and the valve-actuating device mounted between the two parts of the valve chamber; any construction embodying such a two part valve chamber 55 being the full equivalent of the two-unit engine. I, therefore, wish it to be understood that I do not desire to be limited to the details of construction shown and described, for obvious modifications will occur 60 to a person skilled in the art.

Having thus fully described my invention, what I claim as new and desire to secure by Letters Patent, is:—

1. In an explosive engine comprising two 65 units spaced apart and having valve cham-

bers arranged in longitudinal alinement, a rotary valve mounted in both of said chambers, and a valve-actuating device mounted in the space between said units and operatively connected with said valve. 70

2. In an explosive engine having a valve chamber divided into two parts, said parts being arranged in axial alinement, a rotary valve mounted in both parts of said valve chamber, and a valve actuating device mounted between the two parts of said valve chamber on an axis substantially coincident with the axis of said valve, and an operative connection between said valve and said actuating device. 75

3. In an explosive engine comprising two units, a rotary valve comprising separate parts mounted in the respective units and arranged in axial alinement of said engine, and an actuating device mounted between 80 said units, supported independently of said valve and connected with both parts thereof.

4. In an explosive engine having a valve chamber divided into two parts, said parts being arranged in axial alinement, a rotary 90 valve comprising separate sections mounted in the respective parts of said valve chamber, an actuating device mounted between the two parts of said valve chamber, and an adjustable connection between said valve-actuating device and the two sections of 95 said valve, whereby said sections can be simultaneously adjusted relatively to said actuating device.

5. In an explosive engine having a valve chamber divided into two parts, said parts being arranged in axial alinement, a rotary valve comprising separate sections mounted in the respective parts of said valve chamber, an actuating device mounted between 105 the two parts of said valve chamber, supported independently of both sections of said valve and rotatable about an axis substantially coincident with the axis of said rotary valve, and a connection between the 110 two sections of said valve and said actuating device.

6. In an explosive engine comprising two units spaced apart, a rotary valve consisting of two separate parts mounted in the respective units and arranged in axial alinement, a support mounted on one of said units, a valve-actuating device mounted on 115 said support, and means for connecting both parts of said valve to said actuating device 120 to cause them to be actuated in unison.

7. In an explosive engine having a valve chamber divided into two parts, said parts being arranged in axial alinement, a rotary valve consisting of two separate sections 125 mounted in the respective parts of said valve chamber, a support carried by said engine, a valve-actuating device mounted on said support, and a connecting member adjustably secured to said valve-actuating device and 130

- 4
- detachably secured to both sections of said valve.
8. In an explosive engine having a valve chamber divided into two parts, said parts being arranged in axial alinement, a rotary valve consisting of two separate sections mounted in the respective parts of said valve chamber, a support carried by said engine, a valve actuating device mounted on said support, a connecting device interposed between said valve-actuating device and said valve sections, adjustably connected to said valve-actuating device and having means for connecting each of said valve sections thereto in predetermined relative positions.
9. In an explosive engine comprising two units spaced apart, a rotary valve consisting of two separate parts mounted in the respective units and arranged in axial alinement, a support mounted on one of said units, a valve-actuating device mounted on said support, and means for adjustably connecting both parts of said valve to said actuating device to cause them to be actuated and adjusted in unison.
10. In an explosive engine comprising two units spaced apart, a rotary valve consisting of separate parts mounted in the respective units and arranged in axial alinement, means for connecting the two parts of said valve one to the other to cause them to rotate in unison, an actuating device, means for supporting said actuating device independently of said valve, and a connection between said actuating device and said valve.
11. In an explosive engine comprising two units spaced apart, a rotary valve consisting of separate parts mounted in the respective units, each part of said valve having a stem non-circular in cross section extending into the space between said units, a stud mounted on one of the units of said engine and having a longitudinal opening in alinement with said valve, an actuating member rotatably mounted on said stud, a sleeve non-circular in cross section mounted in the opening in said stud and inclosing the adjacent ends of the non-circular stems of the two parts of said valve, and a connection between said sleeve and said actuating member.
12. In an explosive engine comprising two units spaced apart, a rotary valve consisting of separate parts mounted in the respective
- units, each part of said valve having a stem non-circular in cross section extending into the space between said units, a stud mounted on one of the units of said engine and having a longitudinal opening in alinement with said valve, an actuating member rotatably mounted on said stud, a sleeve non-circular in cross section mounted in the opening in said stud and inclosing the adjacent ends of the non-circular stems of the two parts of said valve, outwardly extending arms rigidly secured to said sleeve, and adjustable connections between the outer ends of said arms and said actuating member.
13. In an explosive engine having a valve chamber divided into two parts, a rotary valve consisting of separate sections mounted in the respective parts of said valve chamber, each section of said valve having a stem non-circular in cross section extending into the space between said units, a support carried by one of the units of said engine, an actuating member rotatably mounted on said support, a connecting device carried by said actuating member and having an opening non-circular in cross section to receive the adjacent ends of the non-circular stems of the two sections of said valve.
14. In an explosive engine having a valve chamber divided into two parts, a rotary valve consisting of separate sections mounted in the respective parts of said valve chamber, each section of said valve having a stem non-circular in cross section extending into the space between said units, a support carried by said engine, an actuating member rotatably mounted on said support, a connecting device carried by said actuating member and having an opening non-circular in cross section to receive the adjacent ends of the non-circular stems of the two sections of said valve, the cross-sectional shapes of said hollow connecting device and said stems being such that said stems can enter said hollow device only when in predetermined positions relatively thereto.
- In testimony whereof, I affix my signature in presence of two witnesses.
